WILLIAM F. FALLS, OF BOSTON, ASSIGNOR TO IRA STEWARD, OF MILFORD,
MASSACHUSETTS.

Letters Patent No. 70,822, dated November 12, 1867.

MARBLE-SHOOTER.

The Schedule referred to in these Letters Patent and making part of the same.

TO ALL WHOM IT MAY CONCERN:

Be it known that I, WILLIAM F. FALLS, of Boston, in the county of Suffolk, and State of Massachusetts, have invented an improved Marble-Shooter; and I do hereby declare that the following, taken in connection with the drawings which accompany and form part of this specification, is a description of my invention sufficient to enable those skilled in the art to practise it.

The invention relates to the construction of a device for shooting marbles, by which children are enabled to project marbles with more precision than they can with the thumb and finger, as in the ordinary practice.

The invention consists of a pistol or shooter adapted to hold marbles of various sizes, and having a spring driver, and a trigger and cocking mechanism, with provision for setting the driver at half or full cock, at pleasure, or accordingly as the marble is to be shot a greater or less distance, or is to be thrown with a greater or less impetus.

The drawing represents an instrument embodying the invention, A showing an end view, B a plan, and C a longitudinal central section of the arm or shooter.

a denotes a metal barrel, preferably cast integral with the handle *b*. The rear part *c* of the barrel or tube is made cylindrical, and the front part *d* flaring or trumpet-mouthed, as seen at C. Through the top of the casting, and connecting with the tube *c*, is a slot, *e*; and through the bottom, and opening into the tube, is another slot, *f*. In the rear part of the tube *c* is a spiral spring, *g*; and in the front part thereof a piston or driver, *h*, plays. This driver has a cock, *r*, projecting from its upper side through the slot *e*; and on its under side it has two notches *i*. In an extension, *k*, through which the slot *f* is made, a trigger, *l*, is hung on a pin, *m*, one end of the trigger, or a sere, *n*, thereon, projecting up through the slot, and being pressed up against the piston by the stress of a spring, *o*, forming part of the trigger, the sere slipping into the rear or the front notch *i*, accordingly as the piston is drawn partly or entirely back by the cock *r*. When so engaged, holding the piston in rear position, (or the piece cocked or half cocked,) if the trigger be drawn back, it will turn slightly on the pin *m*, releasing the piston from the sere *n*, when the piston will be projected forward by the expansion or stress at spring *g*.

The marble to be projected is placed in the mouth *d*, the inclination of the sides of which is such that the marble impinges against the surface of the flaring tube, and is thus held in place at any downward angle of the barrel *a*; and the mouth fits any sized marble which may be placed therein.

The operation of the instrument is as follows: The piston is first drawn back, by means of the cock *r*, to either half or full cock, as may be desirable, the sere springing into its notch, as will be readily understood. The marble is then inserted in the mouth *d*; as seen at C, and the piece is ready for discharging. By drawing back the trigger, the piston is released from the sere, when the spring *g* will drive it forward, causing it to impel the marble in the direction in which the instrument may be pointed.

This little instrument is very simple and effective for the purpose for which it is made, and is cheap and enduring.

I claim a marble-shooter, having its parts constructed and arranged to operate, and adapted to the projection of marbles of varying size, substantially as set forth.

WM. F. FALLS.
